INVENTOR
Wm L. Morris
BY
Adam E. Fisher
ATTORNEY

UNITED STATES PATENT OFFICE.

WILLIAM L. MORRIS, OF BROSELEY, MISSOURI.

EGG-CANDLER.

1,393,238.

Specification of Letters Patent. Patented Oct. 11, 1921.

Application filed October 27, 1920. Serial No. 419,799.

To all whom it may concern:

Be it known that I, WILLIAM L. MORRIS, a citizen of the United States, residing in the city of Broseley and State of Missouri, 5 have invented new and useful Improvements in Egg-Candlers, of which the following is a specification, reference being had to the accompanying drawings.

This invention is an egg candler, employing an electric light as an agent for detecting defective eggs. The object is to provide a simple and efficient device of this kind, having means for focusing the light upon the egg, and an automatic arrangement for 15 turning on the light when the device is in use and turning it off when not in use.

In the drawings:

Figure 1 is a top plan view, the left end of the cover being broken away to show the 20 inner construction.

Fig. 2 is a vertical transverse section.

Fig. 3 is a vertical longitudinal section.

Fig. 4 is a detail of the lighting element.

Fig. 5 is a detail of the egg board.

25 The invention consists of a box 1 having a lid 2 hinged at 3 and opening upward at the point 4 after the manner of a trunk lid. Within the box is mounted a sloping egg board 5 extended entirely across the box, and 30 having apertures 6 each adapted to seat an egg 7. Within the box 1 and immediately below the apertures 6 are mounted electric light bulbs 8 set in the circuit 9. Over each of the bulbs 8 are mounted sectional and telescoping light tubes 10-11 which may be 35 telescopically extended or contracted and are frictionally held at any adjustment. These tubes are directed toward the apertures 6. Focusing lenses 12 are mounted in the upper 40 ends of the sections 11. The terminals

13-14 of the circuit 9 are arranged, one in the lid 2 and the other in the box 1, so that when the lid is closed down the terminals fall into contact and so turn the light on, and vice versa as the lid is raised. The light 45 tubes 10-11 are inclined forwardly so as to project the light upon the egg 7 at an angle more convenient to the operator. The operation of the device is apparent from the above description.

50 While I have herein described a certain specific method of constructing and assembling the elements of my invention, it is understood same may be varied in minor details, not departing from the spirit of my 55 invention as defined in the appended claims.

What I claim to be new and patentable is:

1. An egg candler, comprising a box and hinged lid; an egg board within the box; egg holding apertures in the egg board; 60 electric light bulbs below said apertures; an electric circuit through said bulbs; telescoping light tubes over the bulbs and directed toward said apertures; focusing lenses in the upper sections of said tubes; and electric terminals as part of the circuit, and located one on the box lid and the other on the box body, 65 as means for automatically turning the light on or off as the lid is closed or raised.

2. In an egg candler employing a box 70 with a lid, and electric lights for detecting defective eggs, an automatic switch for the lights, embodying electric terminals for the light circuit, located one on the box lid and the other on the box body.

WILLIAM L. MORRIS.
